UNITED STATES PATENT OFFICE.

CHARLES G. SMITH, OF MEDFORD, MASSACHUSETTS, ASSIGNOR, BY MESNE ASSIGNMENTS, TO CAMBRIDGE LABORATORIES, INC., OF CAMBRIDGE, MASSACHUSETTS, A CORPORATION OF MASSACHUSETTS.

ASPIRATOR APPARATUS.

Application filed September 4, 1924. Serial No. 735,817.

In aspirator apparatus for circulating a gaseous fluid with a propellant vapor having a molecular weight greater than that of the gaseous fluid, such as refrigerator systems employing mercury as the propellant and water as the refrigerant, the energy losses are so great that apparatus of this character has not become commercial notwithstanding its apparent theoretical possibilities.

10 I have discovered that the principal losses occur in the aspirator and that they can be largely eliminated by superheating the propellant vapor in the aspirator or before entering the aspirator. By superheating the 15 propellant vapor both its drift velocity through the aspirator and its molecular velocity are increased. Owing to the increased drift velocity the density of the jet may be decreased for a given amount of work, thereby 20 economizing in the quantity of propellant vapor required. Owing to the increased molecular velocity, and also to the decreased density, the mean free path of the molecules is increased, and the two vapors diffuse into 25 each other at a more rapid rate. However the most important feature of the invention consists in bringing the molecular velocity of the heavier propellant vapor up to approximately the molecular velocity of the vapor 30 to be propelled, thereby bringing the drift velocity of the propelled vapor up to its maximum theoretical value and eliminating losses heretofore militating against efficient operation.

35 For the purpose of illustration one concrete embodiment of the invention is illustrated in the accompanying drawings in which the figure is a diagrammatic representation of a refrigerating system comprising a boiler 1, 40 an aspirator 2, an evaporator or cooler 3, a condenser 4, a propellant vapor conduit 5, leading from the boiler to the aspirator, a refrigerant vapor conduit 6 leading from the cooler to the aspirator, a propellant 45 liquid duct 7 leading from the condenser to the boiler, and a refrigerant liquid duct 8 leading from the condenser to the cooler. The propellant liquid 9 (e. g. mercury) stands in the conduit 7 at a height depending upon the pressure in the boiler, and the refrigerant liquid 10 (e. g. water) stands above the column of mercury. The shape of the construction 11 of the aspirator may be adjusted to the different conditions, no attempt

having been made to show any exact shape. 55 It will be understood that both the propellant and refrigerant vapors are condensed together and that the propellant settles to the bottom by virtue of its higher specific gravity. A cooling jacket 12 is shown 60 merely to indicate that the condenser may be cooled and not to restrict the disclosure to any particular cooling method.

In accordance with the present invention the propellant vapor is superheated between 65 the boiler 1 and the outlet of the nozzle 2 and in the particular embodiment shown in the figure the vapor is superheated by means of a heating coil 13 surrounding the nozzle 2 and supplied with the current from suitable source 14. An insulating coupling 16 is preferably provided between the nozzle and duct 5 and suitable insulation 17 (e. g. lava) is placed around the coil 13 to localize the heat in the nozzle. When employing 75 mercury vapor as the propellant and water vapor as the refrigerant the mercury is preferably heated to a temperature of the order of 600° C. By applying an auxiliary source of heat, such as 13, to the mercury 80 vapor, instead of applying all the heat in the boiler 8, all of the aforesaid advantages of superheated propellant vapor may be attained without creating an excess of pressure of the mercury vapor in the boiler. Consequently the height of mercury in conduit 85 7 required to balance the vapor pressure in the boiler may be kept low, whereas if all the heat were applied in the boiler there would be created a vapor pressure so high 90 that the height of conduit 7 would be so excessive as to render the apparatus inapplicable to many situations; and also the density of the vapor would be so great that a nozzle of a practical size would deliver an 95 excessive amount of mercury vapor.

The boiler is preferably constructed so that variation in the height of the liquid therein produces a high variation in the rate of evaporation. This is accomplished in the 100 particular embodiment illustrated in the drawings by making the cross-sectional area of the liquid space surrounding the vertical heater 15 comparatively small so that as the level of the liquid falls less of the heater 105 projects below the level of the liquid and the heater is therefore comparatively ineffective in producing evaporation. Thus as

the pressure in the boiler builds up the level of the liquid in the boiler falls and the rate of evaporation decreases. In this way the rate of evaporation is automatically adjusted to the requirements of the apparatus.

As herein used the term gaseous fluid is intended to comprehend any vapor (as well as any gas) whether the vapor is above or below its critical temperature.

10 I claim:

1. A method for aspirating a gaseous fluid by means of a propellant substance which comprises vaporizing the substance, superheating the vaporized substance to increase the molecular velocity of the vapors and aspirating the gaseous fluid by means of the superheated vapors.

2. A method for aspirating a gaseous fluid by means of a propellant vapor which comprises vaporizing a substance to form the propellant vapor, superheating the vaporized substance to increase its molecular velocity to approximately that of the gaseous fluid, aspirating the gaseous fluid by means of the said superheated vapors and thereafter condensing the said vapors.

3. A method for aspirating a gaseous fluid by means of a propellant vapor having a molecular weight greater than that of the gaseous fluid which comprises increasing the molecular velocity of a propellant vapor having a molecular weight greater than that of the gaseous fluid by superheating the propellant vapor at substantially the point at which the gaseous fluid is to be aspirated, and aspirating the gaseous fluid by means of the superheated vapors.

4. In a refrigerating system a method of cooling the refrigerant liquid material which comprises aspirating the vapors of the refrigerant materials by means of the superheated vapor of a propellant substance having a molecular weight greater than that of the vapor of the refrigerant material, condensing the combined vapors of the refrigerant material and the propellant substance and causing independent recirculation of both the refrigerant material and the propellant substance.

5. In an apparatus of the character described, the combination of an aspirator and means for continuously circulating an aspirating substance to the aspirator, comprising a vaporizer for vaporizing said substance, means for superheating the vapors of said substance before said gaseous fluid is aspirated thereby, means for condensing the vapors of said substance and means for returning said condensed substance to said

vaporizer during the operation of the aspirator.

6. In an apparatus of the character described, the combination of an aspirator, a vaporizer for vaporizing a propellant substance, means for conducting the vapors of said substance to said aspirator, means for superheating the vapors of said substance at the inlet to the aspirator to increase the molecular velocity of the propellant substance, means for condensing the vapor of said substance and means for recirculating said propellant substance during the operation of the aspirator.

7. In apparatus of the character described employing a refrigerant vapor and a propellant vapor having greater molecular weight, a boiler, a condenser, an evaporator, a propellant vapor duct leading from the boiler to the condenser, an aspirator in said duct, a refrigerant vapor duct leading from the evaporator to said aspirator, and means for superheating the propellant vapor after being evaporated in said boiler.

8. In apparatus of the character described employing a refrigerant vapor and a propellant vapor having greater molecular weight, a boiler, a condenser, an evaporator, a propellant vapor duct leading from the boiler to the condenser, an aspirator in said duct, a refrigerant vapor duct leading from the evaporator to said aspirator, and a superheater for increasing the molecular velocity of the propellant vapor to approximately that of the refrigerant vapor.

9. In apparatus of the character described, a boiler containing mercury, an evaporator containing a lighter refrigerant, a mercury vapor duct leading from the boiler to the condenser, an aspirator in said duct, a refrigerant vapor duct leading from the evaporator to said aspirator, and a superheater for increasing the molecular velocity of the mercury vapor to approximately that of the refrigerant vapor.

10. In apparatus of the character described, a boiler containing mercury, an evaporator containing water, a mercury vapor duct leading from the boiler to the condenser, an aspirator in said duct, a water vapor duct leading from the evaporator to said aspirator, a superheater for increasing the molecular velocity of the mercury vapor to approximately that of the refrigerant vapor, and means for superheating the mercury vapor to approximately 600° C.

Signed by me at Boston, Mass., this 28th day of August 1924.

CHARLES G. SMITH.
